UNITED STATES PATENT OFFICE.

MILLER REESE HUTCHISON, OF NEW YORK, N. Y.

DESIGN FOR A DUPLEX HORN.

41,871.

Specification for Design.

Patented Oct. 31, 1911.

Application filed August 2, 1910. Serial No. 575,189. Term of patent 14 years.

To all whom it may concern:

Be it known that I, MILLER REESE HUTCHISON, a citizen of the United States, residing at New York city, in the county of New York and State of New York, have invented a new, original, and ornamental Design for Duplex Horns, of which the following is a specification, reference being had to the accompanying drawing, forming part thereof.

The figure is a side elevation showing the design of the article.

I claim:

The ornamental design for a duplex horn, as shown.

MILLER REESE HUTCHISON.

Witnesses:

J. HAROLSON,
IRVING M. OBREIGHT.
